UNITED STATES PATENT OFFICE.

JOHN BROMAN, OF WORCESTER, MASSACHUSETTS.

TABLE OPERATING MECHANISM.

1,373,050.

Specification of Letters Patent. Patented Mar. 29, 1921.

Application filed March 16, 1920. Serial No. 366,401.

To all whom it may concern:

Be it known that I, JOHN BROMAN, a citizen of the United States, residing at Worcester, in the county of Worcester and State of Massachusetts, have invented a new and useful Table Operating Mechanism, of which the following is a specification.

This invention relates to a table operating mechanism, particularly designed for use in a cloth folding machine. The table of such a machine is gradually moved downwardly as the load of cloth thereon accumulates and is commonly further depressed to permit removal of the cloth. It is then necessary to raise the table to its original position before more cloth can be folded. The table is of heavy construction and frequent repetition of the raising operation is extremely laborious. In fact it is found impossible to employ female or small help on folding machines on account of this table lifting operation.

It is the object of my invention to provide improved table operating mechanism by means of which a heavy table may be easily raised and returned to its original position. In the preferred form I also provide means for adjusting the mechanism to adapt it to different conditions.

An important feature of my invention relates to the provision of a member in the mechanism by which the effect of a spring device on the table is varied as the table rises. My invention further relates to arrangements and combinations of parts which will be hereinafter described and more particularly pointed out in the appended claims.

A preferred form of my invention is shown in the drawings in which—

Figure 1 is a side elevation of my improved table operating mechanism;

Fig. 2 is an enlarged side elevation of an adjustable cam-member;

Fig. 3 is a plan view thereof, and

Fig. 4 is an enlarged detail view of a portion of one of the connecting links.

Referring to the drawings, I have shown herein a folding machine table 10 guided vertically between frame portions 11 and 12, and limited in its upward movement by fixed members 13. A lever 14 is pivoted at 15 to a fixed bracket 16, and is connected by links 17 to bell cranks 18 mounted on fixed pivots 19 and also connected by links 20 to the table 10. One of the bell-cranks 18 is also provided with an additional arm 21

connected by a link 22 to a foot lever 23 mounted on a fixed pivot 24.

Each link 17 comprises telescoping portions 17^a and 17^b, the portion 17^a being recessed to receive the end of the portion 17^b and being also provided with a slot 25 and with an end flange or collar 26. A screw or stud 27 extends through the slot 25 into the portion 17^b and limits longitudinal movement thereof in both directions. A spring 28 is interposed between the flange 26 and a collar 29 on the portion 17^b and yieldingly maintains the link at its extreme length. Whenever either side of the table 10 is depressed to insert an additional fold of cloth, the corresponding link 17 yields to permit such depression without at the same time depressing the opposite side of the table, which would release the cloth already folded.

A spring device 30 is secured to the floor or other fixed support. The device 30 and the lever 14 are connected by chains or other flexible connections 31 and 32 to a double cam-like member 33 mounted on a fixed pivot 34. The cam-like member comprises two portions 35 and 36, the portion 36 being mounted upon the hub of the portion 35 and being adjustably secured thereto by a screw 37 extending through a slot 38 in the portion 36 and threaded into the portion 35. The chain or other flexible connection 31 connects the portion 36 to the lever 14 and the similar chain 32 connects the portion 35 to the spring device 30. A series of holes may be provided in the lever 14, to any one of which the chain 31 may be connected.

Having described the details of construction of my invention the operation thereof is as follows:

Assuming that the table is in lowest position, the parts will be in the position shown in Figs. 1 and 2. The spring device 30 will be tensioned and the chain 32 will be acting at the shortest effective radius of the portion 35 of the cam device 33. At the same time the chain 31 will also be acting at the shortest effective radius of the cam portion 36 of the device 33. Pressure is now applied to the foot lever 23 and the table is moved upward under the combined influence of the lever 23 and the spring device 30, the spring device, however, performing most of the work. The cam device 33 acts as a lever to multiply the movement of the spring device 30 and produces much greater movement of the lever 14.

As the table moves upward the effective radii at which the chains 31 and 32 operate increase in different ratios, while at the same time the springs in the spring device 30 contract and grow weaker. As a net result, the device 30 acts less strongly on the table as the table approaches its upper position. At the same time however, the foot lever 23 has moved downward to a position in which the full weight of the operator may be advantageously applied, so that there is less need for assistance from the spring device 30.

In practical operation, my improved operating mechanism has proved of great value, as a relatively light pressure on the foot lever 23 serves to restore the table to raised position.

Having thus described my invention, it will be evident that changes and modifications can be made therein by those skilled in the art within the spirit and scope thereof as set forth in the claims, and I do not wish to be otherwise limited to the details herein disclosed, but what I claim is:—

1. Operating mechanism for a table, comprising a lever mounted on a fixed pivot, yieldable connections from said lever at points on opposite sides of its pivot to the opposite sides of said table, a spring device,

motion increasing connections between said spring device and said lever, and a foot lever forming a part of said operating mechanism.

2. An operating mechanism for a table, comprising a lever mounted on a fixed pivot, connections from said lever to the sides of said table, said connections each including a compressible link, a spring device, motion increasing connections between said spring device and said lever, and a foot lever connected to operate with said spring device in raising said table.

3. Operating mechanism for a table, comprising a lever mounted on a fixed pivot, separate yieldable connections for said lever to each side of said table, a foot lever, a

spring device, and connections between said spring device and said first lever, said connections including a member flexibly connected to said lever and to said spring device and producing a relatively large movement 50 of said lever corresponding to a relatively small movement of said spring device.

4. Operating mechanism for a table, comprising a lever mounted on a fixed pivot, separate yieldable connections from said lever to each side of said table, a foot lever, a spring device, and connections between said spring device and said first lever, said connections including a member effective to increase the motion between said spring device and said table and to change the effective action of said springs as the table moves vertically.

5. Operating mechanism for a table, comprising a lever mounted on a fixed pivot, 65 separate yieldable connections from said lever to each side of said table, a foot lever, a spring device, and connections between said spring device and said first lever, said connections including a member flexibly connected to said lever and to said spring device and adjustable to vary the movement of said lever and table corresponding to a given movement of said spring device.

6. Operating mechanism for a table, comprising a lever, means to move said lever, and separate connections from said lever to each side of said table, each connection including a compressible link permitting one side of the table to be depressed while the other remains in the same vertical position.

7. Operating mechanism for a table, comprising a lever separately connected to each side of said table, a spring device, a double adjustable cam like member, and flexible 85 connections from said member to said spring device and to said lever.

In testimony whereof I have hereunto affixed my signature.

JOHN BROMAN.
